DRESSER

Ernest Herrmann, Great Neck, N. Y., assignor to
 Home Furniture Co., York, Pa., a corporation
 of Pennsylvania

Application October 24, 1949, Serial No. 5,673

Term of patent 3½ years

(Cl. D33—6)

To all whom it may concern:

Be it known that I, Ernest Herrmann, a citizen of the United States, residing at Great Neck, Long Island, New York, have invented a new, original, and ornamental Design for a Dresser, of which the following is a specification, reference being had to the accompanying drawing, forming a part hereof.

In this showing:

Fig. 1 is a perspective view of a dresser embodying my new design,

Fig. 2 is a side view,

Fig. 3 is a top or plan view, while

Fig. 4 is a bottom view showing the front faces of the front corner posts twisted in a helical plane.

The dominant features of the design reside in those portions shown in full lines.

I claim:

The ornamental design for a dresser, as shown and described.

ERNEST HERRMANN.
